SHOE CONSTRUCTION

John Joseph White, Chicago, Ill., assignor to
 The Florsheim Shoe Company, Chicago, Ill., a
 corporation of Illinois

Application June 11, 1934, Serial No. 729,936

5 Claims. (Cl. 36—30)

This invention has to do with a shoe construction and is concerned more particularly with a shoe having a rubber tread, such as one made of crepe rubber.

5 It is an object of the invention to provide a shoe having the advantages of a leather sole and heel from the standpoint of appearance and the advantages of a rubber sole and heel from the standpoint of wear and comfort.

10 It is another object of the invention to provide a sport shoe of improved construction.

It is a further object of the invention to provide an improved rubber heel construction.

15 It is still another object of the invention to provide a novel process of making an improved heel construction.

A further object of the invention resides in the provision of an improved method for making rubber sole shoes.

20 In accordance with the general features of the invention, after the upper is lasted to the insole and both secured to a welt strip, a strip of smooth-cutting rubber, i. e., in which a smooth surface is formed when cut, such as gasket rubber is cemented over the entire bottom of the shoe. Prior 25 to the application of this sheet, the bottom of the welt and insole may be in the same plane so that no filler material is used, or if desired filler material may be deposited between the channel 30 lips of the insole. After the sheet is cemented in place, a strip of leather such as might remain if the major portion of a leather sole were removed to leave a margin, is stitched vertically to the welt and sheet. Thereafter a sole preferably 35 of rubber material such as crepe rubber is cemented to the portion of said sheet exposed within the strip of leather referred to, and is substantially thicker than the leather strip so as to project substantially beyond the same and provide 40 the tread for the sole.

When the outer vertical surfaces of the welt, sheet and leather strip are finished, the whole presents a smooth finish just as may be found in any leather sole shoe, and yet the rubber sole 45 affords all of the cushioning qualities of rubber soles heretofore employed. The crepe rubber is preferred for the sole, but in the past has been found unsatisfactory because of the fact that its edge becomes easily soiled and tends to become 50 rather prominent after a short period of wear, thereby very materially detracting from the appearance of the shoe.

The heel construction in accordance with this 55 invention is somewhat similar to that of the sole construction except, essentially, that the crepe

rubber heel tread piece, while secured within the confines of the leather strip, is nevertheless formed to overhang the strip to such an extent, especially at the rearmost portion of the heel, as to receive the brunt of the impact with a floor 5 or ground as the step is taken, thereby protecting the adjacent portion of the leather strip which would otherwise become worn rapidly and make the shoe unsightly at the rear, as is common in shoes heretofore in vogue. The crepe rubber 10 being of superior wearing quality, will permit much longer wear of the heel without permitting the heel to become unsightly.

In the making of the heel construction, it is preferred to bevel both the leather strip and 15 the cooperating portion of the crepe rubber tread, and to stitch the leather strip through the gasket rubber sheet and adjacent heel lift. It has been found advantageous to stitch the leather strip before beveling the same since otherwise the 20 stitching has a tendency to crowd toward the bevelled portion and thus provide an unsatisfactory stitching of the strip in place.

Other important objects and advantages of the 25 invention will appear as the description proceeds.

This invention (in preferred forms) is illustrated in the drawing and hereinafter more fully described.

Figure 1 is a bottom plan view of a shoe made 30 in accordance with the principles of the invention, partly broken away to show certain details of the heel construction.

Figure 2 is a fragmentary sectional view taken substantially in the plane designated by the line 35 II—II in Figure 1, and turned through a right angle so as to extend generally horizontally.

Figure 3 is a fragmentary sectional view taken substantially in the plane designated by the line III—III in Figure 1, and

Figure 4 is a view similar to Figure 2 but of a 40 somewhat modified form of the invention.

As shown on the drawing:

Referring now more particularly to the drawing, a shoe in bottom plan view in Figure 1 and constructed in accordance with the present invention includes a heel portion 1 and a sole portion 2 extending forwardly from the heel. In making one form of sole construction embodying the invention, the insole 3 is formed with the usual channel 4, leaving a lip 4a. The upper 5 is lasted over the insole and a welt strip 6 stitched at 7 horizontally to both the upper and the insole. The bottoms of the upper, welt and stitched-in part 8 of the insole are then finished flush. Said stitched-in part 8 projects some- 55

what below the remainder of the insole 3, providing a cavity 9 for the reception of filler material 10 of any suitable composition. One such material comprises asphaltum which is preferably placed in intimate contact with the insole and is covered by a layer of ground cork. The inner portion may if desired be cork which is ground and covered with asphaltum. Other suitable material may be employed for this purpose. The 10 filler material is so placed that its bottom surface is substantially flush with the bottom surfaces of the part 8, upper 5, and welt 6.

These combined surfaces then receive a coating 10a of adhesive such as rubber cement, over 15 which is placed a layer 11 of rubber sheet material which, in a man's shoe, may be about $\frac{1}{16}$ " thick and which is preferably made of a material whose edge will finish smoothly, such as gasket rubber. Prior to this operation, a shank stiffener 20 of metal or other material is secured to the shank of the insole. The sheet of gasket rubber preferably extends throughout the entire shoe from toe to heel.

With the piece of gasket or like rubber thus 25 secured, a strip 12 of leather or other suitable material of the same general form as a welt strip such as would remain if an outsole were cut out to leave a margin of from about $\frac{1}{8}$ " to about $\frac{1}{4}$ ", more or less, of substantially rectangular 30 cross-section, is stitched at 13 to the marginal portion of said piece 11 and the welt 6. This operation leaves a large space 14 bounded at the sides and front by the outsole strip 12. The bottom surface of the layer 11 is then coated with 35 an adhesive 15 such as rubber cement and thereafter there is applied to this adhesive a tread piece or outsole of crepe rubber or rubber of like characteristics of wear as shown at 16. This piece 16 preferably extends rearwardly with the 40 leather strip 12 somewhat beyond the front face 17 of the heel 1 as shown at 18, the portion covered by the heel being preferably skived even with the corresponding ends of the strip 12 so that said end portions of the piece 16 and strip 45 12 may be anchored between the heel portion of the sheet or layer 11 and the heel structure proper. The piece 16 is substantially thicker than the strip 12, preferably projecting downwardly therefrom about $\frac{3}{16}$ ", in a man's shoe. Of course 50 the amount may be varied, but the extent mentioned has been found satisfactory from the standpoint of service as well as from the standpoint of appearance of the shoe as a whole. It is preferably such, in any event, as to protect the 55 surrounding strip 12 from wear, including the toe as the shoe is swung upwardly at the heel about the toe as a center preparatory to taking a step. When the edge of the sole is trimmed, bringing the outer vertical edges of the welt 6, 60 layer 11 and outsole strip 12 flush as shown in Figure 2, blacking or other suitable coating is applied, said surfaces being continuous and smooth and even and giving the shoe a very neat appearance.

65 In the heel construction, after the lifts represented generally by the reference character 19 have been cemented or otherwise secured together, they form a unit which is positioned under the layer 11 extending under the heel as 70 shown at 11a in Figure 3 and, if desired, may be cemented to said layer.

The structure constituting the face lift or top lift of the heel constitutes an important part of the invention and comprises a leather or composition lift 20, a layer 21 preferably of gasket rub-

ber similar to the layer 11 elsewhere described but, of course, in the shape and size of the heel proper, a skeleton strip 22 preferably of leather and a tread piece 23. The layer 21 is preferably cemented to the lift 20, and then the skeleton leather strip of the same cross-sectional form as the strip 12, namely substantially rectangular, is given a substantially horse shoe shape and placed over the margin of the layer 21 so that the outer edges of the parts 20, 21 and 22 are substantially 10 flush. Of course this is done prior to the trimming operation and consequently the edges are made smooth and even in a subsequent operation. The leather strip is thereupon stitched at 24 to the layer 21 and lift 20 so as to positively hold 15 them together as a unit. After this stitching operation, the skeleton strip is cut away at its free inner corner to form a bevel as at 25.

This structure comprising the parts 20, 21 and 22, sewed or stitched together at 24 is then preferably cemented as at 26a to the heel lift structure 19, and thereafter any suitable number of 20 nails, one of which is illustrated at 26, are driven through the layer 21, lift 20, lifts 19 through the 25 heel seat and the insole, the points being turned back into the heel where they are clinched.

Either at this time or before this nailing operation, the inner surface of the skeleton strip is cut on an incline to provide an inner bevelled surface 27. After this structure is nailed in 30 place as mentioned, the bevelled surface 27 and exposed surface 29 of the layer 21 are coated preferably with rubber cement. Then preferably a piece of crepe rubber 23 which has been 35 performed with an outer bevelled surface 28 and shaped to fit snugly within the confines of the strip 22 so that its bevelled surface will engage the bevelled surface 27 and so that its upper 40 surface will at the same time engage the exposed surface 29 of the layer 21, is cemented to said 45 surfaces of the strip 22 and layer 21 as shown in Figures 1 and 3. The piece 23 is of such thickness as to project downwardly substantially beyond the strip 22, an extent of approximately $\frac{3}{16}$ " having been found satisfactory in a man's 50 shoe such as that illustrated. The bevel on the piece 23 enables the same to overhang the bottom surface 30 of the strip 22 to such an extent as to have its edge portion 31 disposed marginally slightly inward of the outer vertical edge 32 of 55 the strip 22. This is especially important construction for the rear part of the heel, where the brunt of the wear on heels occurs. Unless the overhang referred to is provided, the strip 22 at the rear part of the heel is worn very appreciably in a short period of time, as is well known, thereby very materially detracting from the 60 appearance of the shoe. In addition, the cushioned effect obtained by the use of the piece 23 would be partly if not entirely lost. With the 65 overhang, when the heel is first brought down, the overhanging portion of the tread piece 23 is in position to receive the major portion if not the entire impact upon striking of the heel with the ground or floor, thus protecting the strip 22 and at the same time affording the desired 70 cushioning effect.

The bevelling operation on the strip 22 is preferably performed after the stitching operation for the reason that it is found that if the bevelling operation is performed first, the stitching crowds over toward the bevelled portion because of the inability of the bevelled portion to provide proper side support for the stitching operation.

The ends 33 of the stitching 24 are clinched 75

as by nails 34 which may extend into the heel lift structure 19, to firmly secure said ends and prevent their unravelling.

When the vertical surface of the heel structure is trimmed and finished, it has a very neat appearance. Yet, by the provision of the top lift structure as hereinabove described, wear of the rear edge portion of the leather part of the heel is substantially prevented, a cushioned heel tread being provided for comfort.

The gasket rubber may of course be any color and accordingly, if desired, the same may be made in the color in which the associated welt and outsole strips are finished. However, said rubber is of such a character that it will hold any coloring that may be applied thereto, so as to be in harmony with the adjacent contacting parts of the shoe structure.

In Figure 4 a modified sole structure is illustrated. The modification resides in the omission of filler material between the rubber layer 11 and the insole 3. After the welt, upper and insole are stitched together, and the welt turned down to the position shown, the welt, upper and lip resulting from the channel 4 are trimmed substantially flush with the bottom of the insole as shown in Figure 4, the layer of rubber 11 being cemented directly to the substantially continuous surface provided thereby.

It will be appreciated that while the material for certain parts of the structure is described as leather, any other material such for example as leather composition, rubber composition or the like which will give a smooth edge and has the desired strength and durability may be employed. Likewise, the layer material 11 and 23 may also be varied, and is preferably yieldable and compact similar to gasket rubber. Gasket rubber for this purpose has been found suitable because of its being capable of being edge-trimmed and finished with a smooth surface to which dirt will not adhere to any appreciable extent. Crepe rubber layer material is disadvantageous because it does not provide a smooth edge and because its edge holds dirt and in a short period of use has an unrepresentable appearance, and also because its edge will not hold a color finish well.

Lock stitching is preferably employed in holding the sewed parts together.

The outsole 16 may be cemented along its edge to the inner edge 12a of the strip 12. This not only serves to more firmly anchor the outsole, but prevents pebbles and the like from becoming lodged between said edges.

The invention is also applicable to ladies' and children's shoes.

The outsole could if desired be formed to underhang the toe of the strip 12 to the extent and for

the purpose described above in connection with the toplift 23.

The toplift 23 could if desired be rabbeted to receive the inside lower corner (removed in Figure 3 to provide bevelled surface 27) of the strip 22, and thus underhang the latter for the purpose described above.

I am aware that many changes may be made and numerous details of construction may be varied through a wide range without departing from the principles of this invention, that I, therefore, do not purpose limiting the patent granted hereon otherwise than necessitated by the prior art.

I claim as my invention:

1. In a heel construction, a top lift structure comprising a heel lift, a layer of rubber secured thereto, a border strip applied to the margin of the layer and stitched to said layer and lift, and a top lift of cushion rubber substantially integral with said layer and projecting below the strip and constituting the tread of the heel, said top lift being formed to underhang the strip rearwardly at the back of the heel, terminating short of the outer edge of the strip.

2. In a heel construction, a top lift structure comprising a heel lift, a border strip applied to the margin of and stitched to said lift, and a top lift of cushion rubber connected to said lift and of substantially greater thickness than the strip so as to project below the same and constitute the tread of the heel, and means clinching the ends of said stitching.

3. In a heel construction, a top lift structure comprising a heel lift, a border strip applied to the margin of and stitched to said lift, and a top lift of cushion rubber connected to said lift and of substantially greater thickness than the strip so as to project below the same and constitute the tread of the heel, said top lift being formed to underhang the strip rearwardly at the back of the heel and terminate short of the outer edge of the strip.

4. Shoe tread construction comprising an inner layer, a border strip secured adjacent said layer and projecting below the same, providing a cavity, and a cushion tread piece secured in the cavity and projecting below and underhanging the strip so as to space the latter from the ground or other support for the shoe.

5. Shoe tread construction comprising an inner layer, a border strip secured adjacent said layer and projecting below the same, providing a cavity, and a cushion tread piece secured in the cavity to the strip and projecting below and underhanging the strip so as to space the latter from the ground or other support for the shoe.

JOHN JOSEPH WHITE.
